CLAIM

The ornamental design for a magazine holder, as shown and described.

DESCRIPTION

FIG. 1 is a front elevational view of a magazine holder showing my new design;

FIG. 2 is a rear elevational view;

FIG. 3 is a right side elevational view, the left side being a mirror image;

FIG. 4 is a top plan view;

FIG. 5 is a bottom plan view; and,

FIG. 6 is a perspective view thereof, the showing of a mounting bracket by means of broken lines being for illustrative purposes only.

FIG. 1

FIG. 2

FIG. 3

FIG. 4

FIG. 5

FIG. 6
